UNITED STATES PATENT OFFICE.

EDMUND LUNKENHEIMER, OF CINCINNATI, OHIO, ASSIGNOR TO THE LUNKENHEIMER BRASS MANUFACTURING COMPANY, OF SAME PLACE.

SIGHT-FEED LUBRICATOR.

SPECIFICATION forming part of Letters Patent No. 446,993, dated February 24, 1891.

Application filed July 31, 1890. Serial No. 360,458. (No model.)

To all whom it may concern:

- Be it known that I, EDMUND LUNKENHEIMER, a citizen of the United States, residing at Cincinnati, in the county of Hamilton and State 5 of Ohio, have invented certain new and useful Improvements in Sight-Feed Lubricators, of which the following is a description, reference being had to the accompanying drawings, forming part of this specification.
- 10 My invention relates to that class of lubricators which operate on the ascending sight-feed principle, and in some respects is an improvement upon that for which Letters Patent No. 386,596, of July 24, 1888, were granted 15 me.
- The object of my invention is to simplify and cheapen the construction of such lubricators, and its novelty will be herein set forth, and specifically pointed out in the claim.
- 20 In the accompanying drawings, Figure 1 is a side elevation, partly in section, of my improved lubricator. Fig. 2 is a sectional plan view substantially on the dotted line α α of Fig. 1. Fig. 3 is a detail view showing a modification in construction.
- The same letters of reference are used to indicate identical parts in all the figures.
- My improved lubricator, like the one shown 30 in my prior patent above referred to, is designed to be secured to the steam-pipe by a single connection A, this connection having a single channel B for the admission of steam and delivery of oil, and being cast integral with a valve-chamber C, a sight-chamber D, 35 and a shank E, which is screwed into the body of the oil-reservoir F and supports the latter. A steam-condensing pipe G communicates at its lower right-hand end with the interior of the valve-chamber C, as shown and at its lower 40 left-hand end with a passage H in the shank E, which passage communicates with a water-pipe I, extending down inside the oil-reservoir nearly to its bottom. A condensing-bulb J is interposed in the left-hand branch of the pipe 45 G to facilitate condensation of the steam. A valve K controls the passage through the valve-chamber C, both as to the admission of steam to the pipe G and delivery of oil from the sight-chamber D to the channel B in the 50 connection H. The two sides of the sight-
- chamber D are formed of glass disks L, secured in place by cylindrical screw-plugs M with interposed gaskets of rubber or other material.
- A passage N is formed in the inner end of 55 the shank E, around and concentric with the passage H, into which the water-pipe I is screwed. It opens at its upper side into the oil-reservoir and extends downward at its opposite lower side and communicates with an oil-chamber O, immediately beneath the sight-chamber C, an opening P between the two being controlled by a valve Q.
- The connection A, valve-chamber C, sight-chamber D, shank E, and oil-chamber O are 65 preferably cast in one piece. The oil-reservoir F has the usual filling-plug R at its upper end and drain-cock S at its lower end.
- The operation of my improved lubricator 70 is as follows: When the reservoir has been filled with oil and the filling-plug replaced, and the valve K is then opened, the steam will enter the sight-chamber D and be condensed therein, filling the latter with water up to the level of the opening in the dia- 75 phragm in the valve-chamber. The steam also condenses in the pipe G and condenser J and flows down through the passage H and pipe I to the bottom of the oil-reservoir. When the valve Q is now opened, the oil is forced 80 from the top of the oil-reservoir out through the passage N and down into the oil-chamber O, thence through the opening P into the sight-chamber, where it passes up through the water in drops visible through the glass sides 85 of the chamber, and on through the valve-chamber, and out the channel B into the steam-pipe.
- In my former lubricator the sight-chamber 90 consisted of a glass tube supported in fittings at its upper and lower ends and having the oil delivered to its lower end by an oil-pipe extending from the inner end of the lower fitting to the upper part of the interior of the oil-reservoir, as was common in sight-feed lubricators. My present invention dispenses 95 with the oil-pipe on the interior of the reservoir, and also obviates the necessity of connecting the lower fitting of the sight-chamber with the reservoir. A single connection 100

with the reservoir affords passages for both the admission of water from the condensing-pipe and delivery of oil to the sight-chamber, thereby simplifying and cheapening the construction of the lubricator.

My invention is not limited to the form of sight-chamber above described, however, for the advantages of a single connection with the body of the oil-reservoir may be obtained where the usual glass tube is employed for the sight-chamber. This I have illustrated in Fig. 3, where it will be seen that the passage N, opening at its upper end into the oil-reservoir, extends down through a tubular portion T of the casting supporting the lower fitting for the glass tube and delivers the oil through a nozzle into said tube, through which it passes out to the steam-pipe in the usual manner.

While I have illustrated my invention in a lubricator having a single connection with the steam-pipe, it is evident that the condens-

ing-pipe G might have an independent connection with the steam-supply. In such case the valve-chamber C and valve K might be dispensed with and a valve be interposed in the condensing-pipe.

Having thus fully described my invention, I claim—

In an ascending sight-feed lubricator, the combination, with the oil-reservoir, of the connection A, valve-chamber C, sight-chamber D, and shank E, cast in a single piece and provided with the passages H and N, the condensing-pipe G, connected at one end with the valve-chamber C and at its other with the passage H, and the valve K, controlling both the admission of steam to the pipe G and delivery of oil from the sight-chamber D, substantially as described.

EDMUND LUNKENHEIMER.
